UNITED STATES PATENT OFFICE.

EDWARD T. WHEELER, OF AKRON, OHIO.

AIR COOLING SYSTEM FOR AUTO-ENGINE CYLINDERS.

1,300,073.

Specification of Letters Patent.

Patented Apr. 8, 1919.

Application filed March 28, 1918. Serial No. 225,297.

To all whom it may concern:

Be it known that I, EDWARD T. WHEELER, a citizen of the United States of America, and resident of Akron, county of Summit, and State of Ohio, have invented certain new and useful Improvements in and Relating to Air Cooling Systems for Auto-Engine Cylinders.

This invention relates to certain improvements in air cooling systems for motor vehicle engine cylinders; and the objects and nature of the invention will be readily understood by those skilled in the art in the light of the following explanation of the accompanying drawings illustrating what I now believe to be the preferred mechanical expression or embodiment of the invention from among other forms, constructions and arrangements within the spirit and scope thereof.

An object of the invention is to provide means for utilizing air to cool motor cylinders as a substitute for the water cooling systems now generally employed, without requiring radical changes in the exterior design of motor vehicles and without requiring changes in motor construction and that will utilize the cylinder jackets of the water cooling system for the passage of cylinder cooling air blasts or currents.

A further object of the invention is to provide an engine cylinder air cooling system that can be substituted in motor vehicles for the water cooling systems now employed therein, by utilizing the water passages and jackets for passage of cooling air and by substituting a fan casing containing an air forcing fan, in place of the water cooling radiator and fan of the water cooling system.

A further object of the invention is to provide a fan casing approximately simulating the exterior appearance of a water cooling radiator of a motor vehicle, and that can be secured to the vehicle frame at the place usually occupied by such radiator and as a substitute therefor, and that will provide means whereby air can be forced from such casing through the cylinder jackets to cool the cylinders as a substitute for the cooling water of the water cooling system.

The invention consists in certain novel features in construction and in combinations and arrangements as more fully and particularly set forth and specified hereinafter.

Referring to the accompanying drawings:—

Figure 1, somewhat diagrammatically illustrates the front portion of a motor vehicle showing the fan casing of my invention mounted on the frame and connected to deliver cooling air to the motor cylinder jackets, the hood being removed to show the motor.

65

Fig. 2, is a detail perspective view of the fan casing and fan.

Fig. 3, is a section on the line 3—3, Fig. 2.

In the drawings, I show the longitudinal beams 1 of a motor vehicle frame or chassis, 70 and the motor 2. This motor is of any suitable or ordinary internal combustion or explosive type, the cylinders of which are provided with the usual or any suitable jackets for the passage of cooling medium. In the ordinary water cooling system, an upright water cooling radiator is fixed to the frame beams and pipe connections extend therefrom to manifolds or other water passages leading to and from the water jackets surrounding the cylinders so as to provide a continuous flow of water in circuit including the radiator and cylinder cooling jackets as is well understood by those skilled in the art. These water cooling systems also provide a 75 fan between the motor and radiator and driven from the engine or motor shaft to increase the radiation of heat from the radiator and hence aid in reducing the temperature of the water therein. According to my 80 invention, I dispense with the cooling water, the water radiator, the fan behind the same, one of the pipe connections from the cylinder jackets to the radiator, and the water circulating pump, and substitute a fan casing and fan in place of the radiator and 85 couple to the fan casing air outlet, the pipe used in the water cooling system between the upper parts of the motor and radiator. Thus according to my invention, the fan, 90 driven by the motor shaft, will maintain a flow of cooling air from the casing to the motor and through the cylinder jackets thereof and the heated air will be discharged 95 therefrom to atmosphere through the opening at the bottom or lower part of the motor through which water flowed in the water cooling system.

In the specific example illustrated, the fan or blower box or casing 7, is constructed to 110 more or less closely approximate the exterior shape or appearance of the ordinary

water cooling radiator. This casing is strongly constructed of sheet metal and is formed at its lower corners with flanges or lugs 8 to fit the frame beams of the motor vehicle and be bolted or otherwise fixed thereto, although I do not wish to so limit my invention. In fact, the blower casing 7 is ordinarily secured to the frame beams at the usual location of and in approximately the same way as the ordinary water cooling radiator, and is arranged and of about the same shape and dimensions as the water cooling radiator, and if so desired can have a brace, such as 9, applied to its upper portion as is more or less common practice in mounting the water radiator. The fan casing 7 hence extends transversely across the motor vehicle frame and is fixed to the two frame beams and rises vertically therefrom. The fan casing is closed at its bottom, opposite side and top edges by usually imperforate plates or walls 10, while the vertical rear side of the casing is formed by plate or wall 11, having a reduced central air inlet opening 12, and the vertical front side wall of the casing is more or less open for the passage of air and embodies a vertical protective screen 13, preferably of such degree of fineness as to approximately prevent passage of dirt and dust to the fan within the casing.

Within the fan casing I provide any suitable rotor designed to maintain a flow of air for cooling the motor cylinders by passage through the cylinder jackets or otherwise. In the particular example illustrated, I show the fan casing connected up to supply this flow of cooling air to the motor cylinder jackets, through the medium of air pipe 14 at its front end coupled to air outlet 15, at the upper part of the rear wall of the casing, and at its rear end coupled to the manifold 16 at the upper part of the motor and delivering air to the cylinder jackets so that the heated air will discharge from the motor through outlet or discharge port 17 at the lower part thereof, although I do not wish to so limit all features of my invention.

The casing air discharge port or nipple 15, opens into the rear end of an air pocket or pressure chamber *a* formed within the top portion of the fan casing between the front, rear and top walls thereof by an approximately L-shaped partition 18, secured to said walls and providing the pressure chamber or pocket with an open side or inlet *b* located at the front of the pocket with respect to the direction of rotation of the fan rotor.

In the particular example illustrated, the rotor approximately fully occupies the interior of the fan casing and comprises parallel flat vertical front and rear circular side walls 19 having aligned central openings and radial arms 20 fixed to said side walls and to a central fan shaft 21, and uniformly-

spaced radial flat fan blades 22 extending between and fixed to said walls 19 and in width radially of the rotor usually approximately equal to the radial width of the rotor side walls.

The fan rotor is supported and driven by the fan shaft 21 and said shaft is mounted in and supported by arms or brackets 24 fixed to and supported by the front and rear walls of the fan casing. The rear end of the fan shaft is extended rearwardly to the exterior of the casing and is provided with pinion or pulley 25, or other suitable means, for the application of power for rotating the fan rotor at the desired speed. For instance, I show driving chain or belt 26 from or driven by the motor shaft, applied to said pinion 25 for driving the fan. The driving belt 26 is usually the same means utilized to drive the fan employed in connection with the ordinary water cooling systems, although I do not wish to so limit all features of my invention.

The air pocket or chamber in the upper part of the casing, is so arranged with respect to the centrifugal fan rotor, that the outer edges of the fan blades more or less closely sweep the under side of the bottom wall of said pocket, and said pocket will receive the air thrown from and rotating with each blade as it sweeps past the open side of the pocket and air pressure will hence be maintained in said pocket.

The rotor when in action will throw air centrifugally from its blades and hence will cause the body of air around the rotor to rotate therewith and will maintain this body of rotating air under more or less pressure. The air pocket is arranged across the path of rotation of this body of air and directly intercepts the same and hence the pressure in said pocket will cause a constant outflow of air under pressure through outlet 15 to and through the motor cylinder jackets for the effective cooling of the motor cylinders.

My invention can be applied to motor vehicles in the course of manufacture, but also can be readily applied to motor vehicles now in use and equipped with water cooling systems and radiators, as my fan casing can be readily substituted for the water cooling radiator as hereinbefore described.

It is evident that various changes, modifications and variations might be resorted to without departing from the spirit and scope of my invention and hence I do not wish to limit myself to the exact disclosure hereof but consider myself entitled to all such departures as fall within the scope and spirit of the invention.

What I claim is:—

1. An internal combustion motor having a cooling fluid circulating pipe and jacket system, embodying a lower air blast outlet and a top air blast inlet, in combination with

5 a fan casing having an air inlet and an upper air blast outlet connected to supply a blast of cooling air to said inlet of the cooling system, a rotary air blast fan in said casing arranged to draw cool air through said casing inlet and force the same under pressure through said top outlet of the casing.

10 2. An internal combustion motor having a cooling fluid circulating jacket system provided with an upper cooling air inlet and a lower heated air exhaust, in combination with an upright fan casing fixed in front of said motor and simulating a motor-vehicle water-cooling radiator, said casing having a central front air inlet and a top air discharge with an air blast pipe extending therefrom to said cooling air inlet, and a rotary air forcing fan in said casing.

15 20 3. In a motor vehicle engine cylinder cooling system, an upright fan casing in appearance and size approximately simulating the water cooling radiator of the engine water cooling system of such vehicle and constructed and arranged to be substituted for and to be secured to the vehicle frame in place of such radiator, and having an air blast off-take connection constructed and arranged for coupling to the engine cooling 25 water pipe and water jacket system for delivering cooling air through said pipe and water jacket system, and a fan rotor in said casing having means for driving the same from the engine of said vehicle.

30 35 4. In air cooling systems for motor vehicle jacketed engine cylinders, in combination, an upright transversely-arranged fan casing fixed to the front portion of the vehicle frame in advance of the engine, said casing having an air discharge and a pipe therefrom to the engine cooling water pipe and jacket system, from which the water has been drawn, to supply cooling air to the cylinder jacket, said engine having an air discharge from said jacket, and a fan rotor in said casing and operatively connected with and driven by the engine.

40 45 50 5. In air cooling systems for jacketed motor cylinders, a fan rotor arranged to discharge air radially and to rotatively circulate the body of air around the rotor, and an upright casing for said rotor having an internal air pocket open at its front side with respect to the direction of rotation of the

55 rotor and arranged to intercept said air rotating with the rotor, said pocket having a discharge to the exterior of the casing for receiving a pipe to convey the air to the motor.

60 6. In cooling systems for the internal combustion motors of motor vehicles, an upright fan casing having a front air inlet and a rear compressed air discharge, said casing in size and appearance approximately simulating the water cooling radiator of a water 65 cooling system for said motor and being constructed and arranged to be fixed to the vehicle frame in the position ordinarily occupied by said radiator, a fan rotor in said casing, means for coupling the rotor to and 70 driving the same from said motor, and means for coupling said air discharge to the cooling water pipe and jacket system of the motor to maintain a flow of cooling air therethrough in the place of the cooling 75 water.

7. Air circulating apparatus for motor cylinder cooling systems, comprising a fan casing having an air inlet and an internal open-side air pocket with an end outlet to 80 receive an off-take pipe connection, means for securing said casing in a fixed upright position, and a fan rotor within said casing provided with a shaft for driving connection with the motor, said rotor having vertical side walls with center openings and interposed radial fan blades, said air pocket arranged to intercept the body of air rotating with and around said rotor.

8. An air cooling system for internal combustion motors arranged to force cooling air through the jacket system of such motors, comprising an upright fan casing having a closed surrounding edge wall and side walls with center openings, fixed arms bridging 95 said openings, a fan shaft carried by and rotating in said arms and arranged to be driven by the motor, a fan of the inclosed centrifugal type arranged in said casing and carried and driven by said shaft, said casing formed with internal means beyond the periphery of said fan to collect the air compressed by said fan, and a pipe connection to conduct the air blast from said means to the motor jacket system.

100 Signed

EDWARD T. WHEELER.
